UNITED STATES PATENT OFFICE.

WILLARD D. SMITH, OF MAPLEWOOD, MISSOURI.

ADVERTISING DEVICE.

Application filed July 20, 1927. Serial No. 207,077.

This invention relates to animated advertising devices, and more especially, to collapsible advertising devices adapted to bring into prominence a changing display of goods.

5 Among the several objects of the invention is the provision of an article of the type set forth, said article being easily constructed of readily obtainable materials, having a display that effectively attracts the eye of a prospective customer, being easily operable without expensive outlay for power or equipment, and constructed in a manner that permits folding of the completed article so that it may be readily packed or shipped. Other 10 objects will be in part obvious and in part pointed out hereinafter.

The invention accordingly comprises the elements and combination of elements, features of construction, and arrangements of parts which will be exemplified in the structure hereinafter described, and the scope of the application of which will be indicated in the following claims.

In the accompanying drawings, in which 15 is illustrated one of various possible embodiments of the invention,

Fig. 1 is a front view of the assembled display;

Fig. 2 is a side view of the assembled display partly in section, showing the method of operating it;

Fig. 3 is a perspective view of a rotor showing a panel thereof broken away;

Fig. 4 is a fragmentary detail view, partly in section showing the supports of the rotor;

Fig. 5 is a plan view showing the parts of the display dismounted, folded and placed in position for packing; and

40 Fig. 6 is an end elevation of the dismounted display shown in Fig. 5.

Similar reference characters indicate corresponding parts throughout the several views of the drawings.

45 Referring now more particularly to Figs. 1 and 2 there is illustrated at numeral 1 the background board or panel of the display upon which is designated the name, advantages, price, and such features of the article 50 being advertised. It is made from strong, thin stock, preferably wall board. More or less centrally located in this board is an arch-shaped opening 3. Removably mounted with

in this opening or hole is a rotor 5, supported on a shaft 7 which in turn is supported by 55 bearings 9 and 11 located on the front and back, top and bottom respectively of the opening 3 (see also Fig. 4). The reason for this type of mounting will be disclosed herein- after.

The background board or panel 1 is held erect by two supports 13 at opposite ends of said board 1. These supports 13 comprise preferably triangular shaped pieces of wall board or other stock with predetermined angles of support, and are affixed to the board 1 so that they may be folded back against it, into the shipping position shown in Figs. 5 and 6. In order to insure the stability of the display, these supports 13 are cut so that 70 the entire display leans backward. In order to insure free movement of the rotor 5, the shaft 7 is positioned somewhere nearly upright. To accomplish this, the bearings 9 and 11 are set on the front and the back of board 75 1 respectively, as above described (see Fig. 4). Bearing 9 is made of thin spring steel, and bearing 11 is made of a like but heavier piece of metal. Both bearings are affixed to board 1 by bolts 15. Bearing 9 has in it a hole 80 17 adapted to receive the upper end of shaft 7, and bearing 11 is provided with hole 19 adapted to receive the pointed lower end of shaft 7 and permit it to rotate therein. The size and shape of these bearings is regulated 85 by the slope for which the display is fixed and the holes 17 and 19 are placed so that shaft 7 will be substantially upright when the board 1 rests on the supports 13.

The rotor 5 comprises two circular discs 90 or tables 21 and 23 (see also Fig. 3). These discs are made of suitable light stock such as wall board, and have in their centers holes 25 and 27 respectively, through which pass shaft 7. The upper surface of disc 23 has affixed thereto by means of cardboard hinges 29 display panels 31, 33, 35, 37. These display panels are maintained in an upright position by means of tracks, or slots 38, on the under side of disc 21. The tracks 38 individually comprise two shaped pieces of cardboard arranged to leave a space between them sufficiently wide to accommodate the tops of said display panels 31, 33, 35 and 37 and are firmly affixed to said disc 21.

100 In Fig. 3, panel 33 has been removed to

show the construction in greater detail. It will be seen that said display panels are arranged at right angles to each other in the present embodiment of the invention. This is 5 not essential, however, as they may be set at any angle adapted to conform to the number of display panels used. The space between the panels on table 23 is advantageously used to hold articles to be advertised such as are indicated by numerals 51 and 53 in Fig. 1.

The display panels 31, 33, 35 and 37 comprise (separately) frames 42, built of said wall board, with pieces of transparent colored glass, isinglass or similar material 40 15 mounted therein. The quadrants of disc or table 23 are colored with colors complementary to the panels 31, 33, 35 and 37; so that in revolving the entire rotor, striking color effects are obtained.

20 Hingedly affixed to the under side of the disc 23 are a plurality of cardboard vanes 39, adapted to fold back against said disc. These vanes 39 occupy radial positions with respect to disc 23 and shaft 7, and are held in 25 an upright position by tabs 45.

To the under side of disc 21 a wooden block 41 is affixed, and through the center of said block runs a hole adapted to fit shaft 7 tightly. This arrangement is made to affix 30 the rotor 5 as a whole to shaft 7 so that it may not revolve thereon. Cotter pins 43 through shaft 7 prevent the lower disc 23 from sliding upwardly or downward upon said shaft.

35 In Figs. 5 and 6 is shown the display in a dismounted form. It is readily seen how shipment is facilitated by the flat nature of the dismounted parts. The supports 13 fold back flat against the back of background 40 panel 1. The rotor is removed from its bearings by springing said bearings and the display panels 31, 33, 35 and 37 fold down on their hinges after the disc 21 is slipped from the shaft 7. Disc 23 is removed from shaft 7 45 and the vanes 39 are folded back against disc 23. The parts are all, therefore, substantially flat, and they may be laid on one another in any arrangement (Fig. 5 is typical) rendering packing and shipping extremely 50 simple. The small hardware (including wooden and metal parts) may be wrapped separately and included in the one flat parcel.

To assemble the display from the folded parts as shipped, one proceeds as follows:

55 First, stand the background board 1 upon its supports 13. Second, place the cotter pins 43 in the shaft 7 after placing the disc 23 on said shaft, panels upward. Hinge the display panels to their open positions. Next, 60 force the wooden block 41 with disc 21 attached, on said shaft, so that the side of disc 21 with the tracks thereon is downward. The block 41 is forced down until the tracks or slots on the under side of disc 21 engage the 65 top edge of display panels 31, 33, 35 and 37

and hold them firmly. Bend the vanes 39 to an upright position and secure them in this upright position by means of tabs 45. To complete the assembly, place the shaft 7 with the now completely assembled rotor affixed thereto in its bearings 9 and 11.

To operate the device, the preferred form of motive power used to drive the rotor is air in motion, while an electric light with a reflector 47 provides the light necessary. In 75 the figure shown, an electric fan 49, by means of its driving force on vanes 39, serves to turn the rotor at a speed regulated by the speed of the fan.

The fan may also be directed as shown by 80 the dotted lines in Fig. 2; so as to act with a tangential component on the rotor 5 and prevent the greater part of the air current from traveling through the opening 3. A thermal flasher device 55 may be inserted in 85 the line feeding the fan, so that the fan circuit is turned on and off intermittently. Any similar automatic current controlling means may be used. In this case it is desirable to use a stopping arrangement to cause the rotor to 90 stop at a predetermined position when its motive power is cut-off. To this end, a pair of leather flaps 57 (Fig. 1) and a series of pairs of pins 59 are provided on the background board 1 and the table 23 respectively. 95 This combination of elements acts to stop the rotor at predetermined positions when the air from the fan is turned off intermittently.

It is understood that other forms of drivers may be used such as an electric motor coupled 100 directly to shaft 7 to rotate said shaft.

With the rotor moving at a suitable speed, the light being focused properly, a novel and animated color effect is obtained by viewing the display from the front.

105 In view of the above, it is believed that the various features of this invention will be clear without further elaboration, and it will be seen that with the apparatus, method and results herein described, the several objects 110 of the invention are achieved and other advantageous results attained.

As many changes could be made in carrying out the above invention without departing from the scope thereof, it is intended that 115 all matter contained in the above description shall be interpreted as illustrative and not in a limiting sense.

I claim:

1. The display device comprising a sloping background panel, at least one opening therein, a rotor adapted to rotate in said opening, said rotor being mounted on bearings located forwardly and rearwardly of said background panel.

120 2. The display device comprising a background panel sloping rearwardly and upwardly, at least one opening therein, a rotatable member mounted in said opening on an upwardly located bearing ahead of said panel 130

and on a downwardly located bearing behind said panel.

3. The collapsible display comprising a background panel, at least one opening there-
5 in a shaft passing through said opening and supporting a rotor and supported by bear-
ings, the plane of the background panel in-

tersecting said shaft at an angle between the bearings.

In testimony whereof, I have signed my ¹⁰ name to this specification this 18th day of July, 1927.

WILLARD D. SMITH.
